SAFETY DEVICE FOR SETTING OFF
EXPLOSIVE CHARGES

Russell G. Martin, Russellville, W. Va.

Application September 19, 1947, Serial No. 774,924

3 Claims. (Cl. 175—115)

1

This invention relates to ignition devices for explosives and more particularly to a portable ignition device for use in mines and the like for setting off explosive charges.

A main object of the invention is to provide a novel and improved safety device for setting off charges of explosive which is very simple in construction, compact in size, and reliable in operation.

A further object of the invention is to provide an improved safety device for use in mining operations, and the like, in setting off explosive charges, said device containing the source of current for igniting the explosive and being arranged so that the explosive cannot accidentally be set off while the wiring connections thereof are being made to the device, thereby reducing hazards to miners, and at the same time, providing effective control of the ignition of the explosive.

Further objects and advantages of the invention will become apparent from the following description and claims; and from the accompanying drawings, wherein:

Figure 1 is an elevational view showing a safety explosive ignition device constructed in accordance with the present invention, the hinged cover of the device being shown in open position.

Figure 2 is a top view of the ignition device of Figure 1 with the cover in closed position.

Figure 3 is an enlarged cross-sectional detail view taken on line 3—3 of Figure 1.

Referring to the drawings, 11 designates a generally rectangular housing, preferably of insulating material, provided with a cover 12, hinged to the housing at 13, 13. Received in the housing 11 are a pair of flashlight battery cells 14 and 15, cell 15 being inverted, as shown in Figure 1. Secured to the bottom wall of housing 11 beneath the cells 14 and 15 is a U-shaped contact spring 16 which engages the bottom of the metal casing of cell 14 at one arm thereof and engages the center positive pole contact of the inverted cell 15 at the other arm thereof.

The top wall of housing 11 is apertured immediately above the center positive pole contact of the cell 15 and secured to said top wall around the aperture therein is a metal washer 17. Passing slidably through the washer is the shank of a headed bolt or pin 18 to the bottom end of which is secured a collar member 19, preventing upward removal of the bolt 18 from the washer 17. A coiled spring 20 encircles the shank of bolt 18 and bears between the head of the bolt and washer 17, thereby biasing the bolt upwardly. When bolt 18 is manually depressed, the bottom

2

end thereof engages the center positive pole contact of cell 14.

Secured to the top wall of housing 11 by a bolt 21 is an angle bracket 22, and pivotally secured to the upstanding arm of bracket 22 is a lever bar 23 which is swingable in a transverse vertical plane of housing 11. The angle bracket 22 is located adjacent the front edge of said top wall, and secured to said top wall adjacent its rear edge is a second angle bracket 24. Pivotally secured to the upstanding arm of bracket 24 is a lever bar 25 which is swingable in the same transverse vertical plane as lever bar 23. Secured to the top wall of housing 11 between the angle brackets 22 and 24 is an upstanding boss 26 of insulating material, and secured to the top of said boss in the transverse plane of lever arms 23 and 25 is a metal bar 27, the ends of said bar 27 being normally spaced from the lever bars 23 and 25 by the biasing action of respective coiled springs 28 and 29 which bear between suitable recesses formed in boss 26 and the adjacent inner edge portions of the respective lever bars 23 and 25. The bottom ends of the lever bars bear against the top wall of the housing, thereby limiting outward rotation of the lever bars under the biasing force exerted thereon by the springs 28 and 29. The upper portions of the outer edges of the lever bars 23 and 25 are formed with respective arcuate notches 30 and 31 providing finger engaging means for rotating the lever bars inwardly. By exerting squeezing pressure on said lever bars with the fingers, the lever bars are simultaneously brought into contact with the ends of the bar 27.

Secured to the bottom surface of the housing 11 top wall by bolt 21 is a bowed contact spring 32 which engages the bottom of the metal casing of the inverted cell 15. Secured to the top wall of the housing 11 between washer 17 and boss 26 is a transverse terminal block 33 of insulating material provided with spaced terminal jacks 34 and 35. Washer 17 is connected to terminal jack 34 by a wire 36 and bracket 24 is connected to terminal jack 35 by a wire 37. The external ignition element, not shown, is connected to the jacks 34 and 35 by wires 38 and 39 provided with male prongs which are plugged into the respective jacks.

When the charge of explosive is to be detonated, lever arms 30 and 31 are squeezed together with the fingers so that they engage the ends of bar 27, and the head of bolt 18 is pushed downwardly so that its bottom end engages the center positive terminal of cell 14. This completes the detonating circuit, said circuit comprising wire

38, jack 34, wire 36, washer 17, bolt 18, cell 14, spring 16, cell 15, contact spring 32, bolt 21, bracket 22, lever arm 23, bar 27, lever arm 25, bracket 24, wire 37, jack 35, and wire 39.

It is to be noted that the detonating circuit is normally open at three points, namely, at lever arm 23, at lever arm 25 and at contact bolt 18, so that accidental detonation cannot occur when the wires 38 and 39 are connected to the jacks 34 and 35.

The cover 12 is normally secured in closed position by a hook latch 48 pivotally connected thereto which is engaged with a pin 41 projecting from the side wall of housing 11.

While a specific embodiment of an ignition device for setting off explosive charges has been disclosed in the foregoing description, it will be understood that various modifications within the spirit of the invention may occur to those skilled in the art. Therefore it is intended that no limitations be placed on the invention except as defined by the scope of the appended claims.

What is claimed is:

1. A portable shot firer comprising an insulated box-like casing having top and bottom walls, a pair of vertically disposed dry battery cells arranged in inverted, side by side position in said casing and substantially filling the space between said top and bottom walls, a conductive spring on said bottom wall bridging the terminals on the lower ends of said cells, a spring retracted plunger contactor mounted on and operating through said top wall, said contactor being arranged to engage the upper terminal of one of said cells when depressed, a pair of laterally spaced lever contactors pivotally mounted on said top wall to swing inwardly toward each other from outward starting positions, a bridging block mounted on said top wall between said levers, spring means normally yieldably maintaining said levers in their outward starting positions in which said levers are out of contact with said bridging block, a conductive spring on the underside of said top wall engaging the upper terminal on the other of said pair of cells and connected to one of said lever contactors, a pair of jacks mounted on said top wall, and means severally connecting the remaining lever contactor and said plunger contactor with said jacks, whereby an electrical detonator connected to said jacks can be detonated only while said plunger contact is held in depressed position and both of said lever contactors are held inwardly against said bridging block.

2. A portable shot firer comprising an insulat-

ed battery case containing battery means having a pair of terminals, a spring retracted plunger contactor on said case engageable only in its impressed position with one of said terminals, a pair of lever contactors, means pivoting said levers for movement toward and away from said other, spring means normally maintaining said levers yieldably in spread relation, a bridging block on said case between said levers with which said levers are out of contact in their normal spread positions, means connecting one of said lever contactors with the other terminal of said battery means, and a pair of jacks on said case severally connected to the remaining lever contactor and said plunger contactor, whereby an electrical detonator connected to said jacks can be detonated only while said plunger contact is held in in-pressed position, and both of said lever contactors are held in inward positions in engagement with said bridging block.

3. A shot firer comprising an insulated support, a spring retracted plunger contactor on said support, a contact with which said plunger contactor is engageable only while pressed in, a pair of lever contactors pivoted on said support for movement toward and away from each other, spring means normally separating said lever contactors, a bridging block on said support between said lever contactors and with which said lever contactors can engage only in inwardly swung positions, said lever contactors being independently swingable between their normal spread positions and their inwardly swung positions, a pair of jacks on said support severally connected to said plunger contactor and one of said lever contactors and to which opposite sides of an electrical detonator are adapted to be connected, and means for connecting the opposite sides of a current source to said contact and to the other of said lever contactors, whereby the detonator can be detonated only while said plunger contactor is in its in-pressed position and both of said lever contactors are in inwardly swung positions in engagement with said bridging block.
